No. 887,769.

PATENTED MAY 19, 1908.

T. M. CAVEN.
ELECTRICAL CURLING IRON.
APPLICATION FILED DEC. 11, 1906.

UNITED STATES PATENT OFFICE.

TREVOR M. CAVEN, OF KANSAS CITY, MISSOURI, ASSIGNOR TO ISAAC C. SOULE, OF KANSAS CITY, MISSOURI.

ELECTRICAL CURLING-IRON.

No. 887,769.

Specification of Letters Patent.

Patented May 19, 1908.

Application filed December 11, 1906. Serial No. 347,269.

To all whom it may concern:

Be it known that I, TREVOR M. CAVEN, a citizen of the United States, residing at Kansas City, in the county of Jackson and State 5 of Missouri, have invented certain new and useful Improvements in Electrical Curling-Irons; and I do declare the following to be a full, clear, and exact description of the invention, such as will enable others skilled in the art to which it appertains to make and use 10 the same, reference being had to the accompanying drawings, and to the letters and figures of reference marked thereon, which form a part of this specification.

15 My invention relates to curling irons, and more particularly to a device of that class which receives its heat from a unit contained in one of the bars of the iron, and is connected with a suitable source of electrical supply. 20 It is the object of my invention to provide an iron of that class having a heating unit of limited resistance which may be placed in series with a lamp or other article adapted to receive electrical energy, in a manner to prevent 25 over-heating of the iron. In accomplishing this object I have provided the improved details of structure which will presently be fully described and pointed out in the claims, reference being had to the accompanying 30 drawings forming part of this specification, in which like reference numerals refer to like parts throughout the several views, and in which—

Figure I is a general view of a curling iron 35 constructed according to my invention, shown in combination with an incandescent lamp. Fig. II is an enlarged view in central longitudinal section of an iron constructed according to my invention, and a swivel 40 which I use in connection therewith. Fig. III is a similar view of a modified form of coil, showing the swivel in full lines. Fig. IV is a detail view of a still further modified form of heating unit. Fig. V is a similar 45 view of a further modified form of heating unit. Fig. VI is a circuit diagram.

Referring more in detail to the parts—1 indicates a cylinder which forms part of one of the forks of a curling iron, and carries a 5 handle 2, as shown in Figs. II and III, or is curved and extended to form a handle portion 2', as shown in Fig. I. Located in cylinder 1 is a heating unit 3, the preferred form of unit being the coil shown in Figs. II and III,

which is wrapped on a suitable core 4, and 55 provided with a packing 5, between the coil and cylinder shell.

The ends 6 and 7 of the coil are extended 60 backwardly through a channel in handle 2 or through the integral handle portion 2', to a socket 8, where the end 7 is soldered or otherwise secured to the bottom of a well 9, of brass or other conductive material, which is threaded at its outer end into a fiber or like collar 9' carried in a brass or like tube 10, 65 which tube is of such diameter as to fit loosely into socket 8.

Seated in well 9 is a coil spring 11, and resting on spring 11, with its free end projecting 70 out of well 9 is a plunger 12, both the spring 11 and plunger 12 being of a suitable conductive material.

Fitting loosely within the outer end of tube 10 is an offset hollow neck 13, the outer 75 end of which projects beyond socket 8, while its inner end contains an insulated longitudinally perforated plug 14. Extending through neck 13 is a wire 15, the inner end of which projects into the perforation in plug 14 and is there anchored by a screw 16 80 having a head 17 adapted to contact with the outer end of plunger 12. Threaded onto the outer end of tube 10 is a cap 18 having a perforation in its head through which neck 13 projects, and in which said neck may 85 freely revolve while the inner surface of said head covers the offset portion of the neck to prevent its escape from the socket; cap 18 being of a diameter to fit snugly into socket 8, and is adapted when so fitted to 90 bind the second coil wire 6 between its outer surface and the inner surface of the socket.

Fitting snugly over the outer end of neck 13 is an insulated button 19 having a longitudinal perforation therein, through which 95 the wire 15 extends and into which a second wire 20 projects, the latter being anchored between the outer surface of neck 13 and the inner surface of said button when the latter is forced over the former.

100 Wires 15 and 20 may be wrapped together to form the cord 21 and lead to a socket 22 carried by a bracket 23. Socket 22 has a suitable mechanism for contact with the feed wires in the bracket and one of the 105 wires 15—20 contacts with such mechanism and the other with the parts which conduct a current to the lamp bulb so that the cur-

rent from the feed wires must pass through the coil in the curling iron cylinder and through the lamp. The coil in the curling iron cylinder is composed of wire having a resistance only sufficient to heat the curling iron to a desired temperature so that should the iron be attached to a socket having feed wires of a higher potential than is necessary for the proper operation of the iron the excess will pass through the curling iron coil into the lamp. In this manner the curling iron may be used with a current of any strength, without danger of overheating the iron or burning out the coil.

15 25 is a plug located in the end of cylinder 3 and 26 is a clip of any ordinary construction, having ears 27 through which the pivot pin 28 projects; said pin also projecting through cylinder 1 between the coil ends 20 and serving as an anchor to prevent the displacement of the coil.

29 is a spring adapted to normally retain clip 26 in yielding engagement with cylinder 1.

25 In assembling the parts the wire 6—7, is projected through the cylinder 1, coiled on the core 4 and returned to the cylinder and packed with the asbestos or suitable insulating body 5. The end plug 25 is then secured in position and the wire end 7 secured to the well 9. The wire 15 is then secured in its plug by means of screw 16 and the button pushed over neck 13, anchoring wire 20. The parts carried in socket 8 are forced 35 into place, anchoring the end 6 of the curling iron coil, and the other parts arranged in the customary manner.

When the current is turned on, a circuit is made through the screw 16, the head of which contacts with plunger 12, and the spring 11 which connects the plunger and bottom of well 9 to which the end 7 of the curling iron coil is secured. On the return, the coil end 6 contacts with cylinder 10 45 which carries neck 13, the latter having a contact with the feed wire 20.

As the curling iron is turned in handling, neck 13 revolves freely in the cylinder and anchor cap without turning cord 21 so that 50 "kinking" or binding of the cord 21 is obviated, although a perfect contact between the movable and stationary parts of the swivel is always had through the yielding plunger 12.

55 As before stated, my preferred form of heating unit, is the coil shown in Fig. I and described in detail in the present specification, although, a number of modified forms of heating unit may be utilized according to 60 the general principle of my improved device.

In Fig. II I show the coil which is secured to a coupling block A, with the wires 6—7 connecting block A with the swivel.

65 In Fig. IV I show a bulb D containing suitable filaments the bulb being carried in

the socket E, and the wires F—G being connected with the socket and with the swivel (not shown in either of views IV and V).

In Fig. V I show a heating rod H, carried between block I and a socket J, with a wire 70 K running through the block and connected with the outer end of the rod and a wire L connecting the inner end of rod H with the swivel, so that when current is applied a circuit is made through the parts.

75 While I have specifically described the swivel which I use in connection with my iron, I make no claim thereto in this application, as it is shown and claimed in the application, filed by me the 18th day of May 1907, which is serially numbered 374,362.

80 Having thus described my invention, what I claim as new therein, and desire to secure by Letters Patent is,—

85 1. A curling iron comprising a hollow bar, a heating coil wrapped on a suitable core and contained in said bar, feed wires connected with said coil, a clip adapted for co-operation with said bar, and a pivot pin extending through portions of said clip and through the hollow bar between the coil ends and adjacent to the coil body for the purpose set forth.

90 2. A curling iron comprising a heating bar, a handle portion, a heating unit contained in said bar, a swivel carried by said handle portion, means for conducting current to said swivel, and means for conducting current between said swivel and said heating unit independently of the heating bar and handle portion.

95 3. In a curling iron, the combination with a suitable bar and handle portion, of a stationary swivel member carried by said handle portion, a movable swivel member carried by said stationary member, feed wires connected with said movable member, a heating unit in said bar, and feed wires connecting said stationary swivel member and 100 said heating unit independently of said heating bar and handle portion.

105 4. In a curling iron, the combination with a heating bar having a non-conductive handle portion, of a stationary swivel member carried by said handle portion, a movable swivel member carried by said stationary member, feed wires connected with said movable member, a heating unit carried in but insulated from said bar, and conducting 110 wires connecting the heating unit and stationary swivel member.

115 5. In a curling iron, the combination with a hollow bar, of a handle portion on said bar, a heating coil contained in said bar with its ends projecting into said handle portion, a stationary swivel member contained in said handle portion and having separate contact with each of the coil ends, a movable swivel member carried by said stationary member, 120

125 130

feed wires carried by said movable member, and means for passing a current between said members, for the purpose set forth.

6. A curling iron comprising a hollow bar 5 provided with a handle portion, a heating coil contained in said bar with its ends projecting into said handle portion, a plug in said handle portion having a separate contact with each of the coil ends, a neck mov- 10 ably mounted in and projecting from said plug, feed wires in said neck, and means for completing a circuit through said feed wires and coil.

7. A curling iron comprising a heating bar 15 having a handle portion, a plug carried by said handle portion, a neck movably mounted in and projecting from said plug, a feed wire connected with said neck, a second feed wire carried by but insulated from 20 said neck, a heating coil in said bar having one end connected with the body of said plug and its other end connected with means carried by but insulated from said plug and having contact with the second feed wire 25 carrying parts, for the purpose set forth.

8. In a curling iron, the combination with a heating bar having an extended handle portion, a tube in said handle portion having a suitable cap, a rotary neck partially located 30 in and projecting from said tube, a feed wire carried in but insulated from said neck, a second feed wire having contact with said neck, a coil in said heating bar having one end in contact with said tube and its other 35 end in contact with means carried by but insulated from said tube, and means for transmitting a current between said first wire and the insulated end of said coil.

9. In a curling iron, the combination with 40 a heating bar having a handle portion, of a tube in said handle portion having a suitable cap, a rotary neck partially located in and extending from said tube, an insulated plug in said neck, a feed wire extending into said 45 plug, a pin adapted to anchor the feed wire in said plug and having a head projecting into said tube, a second feed wire, having contact with said neck, a coil in said bar, having one end in contact with said tube, 50 and means, insulated from said tube, whereby a current may be transmitted from the plug feed wire to the second coil end, for the purpose set forth.

10. In a curling iron, the combination with 55 a heating bar having a handle portion, of a tube in said handle portion, having a suitable cap, a rotary neck partially located in and extending from said tube and having a shoulder adapted to abut against the inner surface 60 of said cap, an insulated plug in said neck, a feed wire extending into said plug, a keeper for securing said feed wire in said plug, and having a head projecting into said tube, a second feed wire having a contact with said 65 neck, a conductor carried by but insulated

from said tube and having a yielding contact with the head of said keeper, and a coil in said bar having one of its ends in contact with said conductor and the other in contact with said tube.

11. In a curling iron, the combination with 70 a heating bar having a handle portion, of a tube in said handle portion, having a suitable cap, a rotary neck partially located in and extending from said tube, a feed wire carried by but insulated from said neck, conductive means connecting said wire with the interior of said tube, conductive means carried by but insulated from said tube and adapted for yielding engagement with the conductive 80 means connected with the feed wire, a coil in said bar having a contact with the tube and with the insulated conductor carried by the tube, and a second feed wire connected with said neck.

12. In a curling iron, the combination with 85 a heating bar, of a rotary neck carried by said bar, feed wires suitably connected with said neck, a plunger, a spring adapted to yieldingly retain said plunger in conductive 90 relation with one of said feed wires, a coil in said bar having one of its ends in conductive relation with said plunger, and means for completing a circuit between the other end of said coil and the second feed wire.

13. In a curling iron, the combination with 95 a heating bar, of a rotary neck carried by said bar, feed wires suitably connected with said neck, a contact head connected with one of said wires and projecting from said neck, 100 means in contact with and adapted for supporting a well adjacent to said neck, a well supported by but insulated from said means, a coil spring in said well, a plunger resting on said spring and adapted for yielding contact 105 with said head, and a coil in said bar, having one of its ends connected with said well and the other with said supporting means, substantially as set forth.

14. In a curling iron, the combination with 110 a heating bar, of a rotary neck, feed wires suitably connected with said neck, a contact head connected with one of said wires and projecting from said neck, means in contact 115 with said neck for supporting a well adjacent to said contact head, a well supported by but insulated from said means, a coil spring in said well, a plunger resting on said spring and adapted for yielding contact with said head, and a coil in said bar having one of its ends 120 connected with said well and the other with said supporting means, substantially as set forth.

15. In a curling iron, the combination with 125 a heating bar having an extended handle portion, provided with a socket, of a perforated cap fitting tightly within said socket, a tube carried by said cap, a neck revolvably mounted in said tube and projecting through the perforation in said cap, a feed wire ex- 130

tending through and insulated from said neck, a keeper for securing said wire in position and having a contact head projecting into said tube, a second feed wire in conductive relation with said neck, a button covering the outer end of said neck and binding the second feed wire thereagainst, a well carried by but insulated from said tube, a coil spring in said well, a plunger in said well,
5 with its outer end held in yielding contact
10 with said keeper head, and a coil in said bar,

having one end secured to said well, and the other end anchored between the tube cap and the inner surface of said extended handle portion, substantially as and for the purpose 15 set forth.

In testimony whereof I affix my signature in presence of two witnesses.

TREVOR M. CAVEN.

Witnesses:

JOHN F. WADE,
A. M. MAXWELL.
